RIFFLE

Harry W. Bell, Seattle, Wash., assignor to Durable
Mat Company, Seattle, Wash., a corporation of
Washington

Application July 9, 1935, Serial No. 30,460

2 Claims. (Cl. 209—506)

My invention relates to riffles such as are employed for catching and segregating gold values, particularly fine dust.

Placer mining or dredging operations always take place in relatively remote spots, generally requiring packing in for considerable distances over rough country. Weight is therefore an item of considerable moment. Replacement or repair of equipment is seldom easy to accomplish, and suspension of operations because of break-down of equipment becomes a serious matter, especially where, as in certain parts of Alaska, the working season is a comparatively short portion of the year.

Aside from the first object of all riffles, namely, to catch the gold, and all of it, it is a primary object of this invention to provide a riffle unit which is light in weight, durable, and readily repairable on the spot, and which is therefore admirably suited for use under the conditions outlined above.

It is a further object to make a riffle of material which is largely waste and available in large quantities, and which can therefore be made and sold cheaply, a material fulfilling these requirements being rubber tire casing material, particularly but not essentially the tread portion of such casing.

It is especially an object to provide a riffle which is efficient and rapid in saving the gold, so that large quantities of gold-bearing gravel and sand may be worked through the riffle, thus making it economically possible to handle larger quantities of material in which the gold-bearing content may be relatively low, for example, even tailings of old workings.

Since fine gold particles worked in a riffle will find their way into seemingly impenetrable crevices it is a further object to provide a riffle which, though it may be made of individual strips with spacer elements between them, may yet be made tight at all joints to prevent secretion of gold in the joints between the riffle elements and the spacers.

It is a still further object to provide a riffle which can be readily handled as a unit, and can be readily lifted and removed from the deposited sand, clay and gold at clean-up times.

It is a further object to provide a riffle which may readily be formed in various patterns to suit the individual taste or desire of the user.

A further object is to provide a riffle unit so formed that through the action of the water, gravel, sand and the like moving thereover it will automatically free itself from any gravel which

may tend to lodge between the riffle elements, thereby automatically preventing clogging of the riffle units.

My invention comprises the novel riffle unit and the novel riffle element and their relative combination and arrangement, as shown in the accompanying drawing by way of illustration, and as will be made clear in this specification and more particularly defined by the claims terminating the same.

Figure 1 is a perspective view, with parts broken away, showing two such riffle units in a sluice box.

Figure 2 is in part an elevation and in part a section through such a riffle unit.

Figure 3 is a section taken transversely across a riffle unit of somewhat modified form.

The sluice box in itself forms no part of my present invention, and that shown is merely a typical sluice box by way of illustrating the manner in which my riffle unit may be incorporated in such a sluice box. It comprises the bottom 4, sides 40 and 41, supporting and bracing elements 42, and hold-down elements 43 secured inside the sides 40 and 41 to hold the riffle units in place resting upon the bottom 4.

In a typical form, illustrated in the drawing, the riffle unit comprises a plurality of strips 1 cut from rubber tire casing material. Old solid rubber truck tires may also be cut into strips and used for this purpose. Rods 2 pass through a number of such strips, spacer elements 3 holding the latter spaced apart, and nuts 20, threaded on the rods, hold the spacers and strips together so that the whole, in the form illustrated, comprises a grid in which the strips 1 are held on edge in parallel spaced-apart face-to-face relationship, and with the strips extending transversely to the direction of water flow, indicated by the arrows F. Preferably the strips are so arranged that while generally upright they are somewhat inclined to the direction of water flow, and I consider it preferable to leave the tread surface, when the strips are made of tread material, as is preferable, on the upstream side of the water flow, so that the natural transverse concavity of the material tends to curve its upper edge downstream. This is shown in Figure 2.

An advantage of this is that there is presented first to rocks or gravel, as indicated at R, the comparatively thick, tough rubber of the tread, as the gravel rolls downstream, and in addition there is formed a sharp edge on the downstream side, stiffened and reinforced by the embedded fabric 10, over which the water ripples and eddies,

thus breaking up its direct flow and effecting rapid deposition of the gold, as indicated at G. It has been found that riffles formed of metal, in addition to weighing excessively, wear away comparatively rapidly under the abrasive effect of the sand and gravel, but the rubber, while sufficiently stiff to form the eddy currents, does not wear away, and by its inherent elasticity and flexibility yields somewhat to the pounding of the gravel, and is continually flexing, and it is a proven fact that it does not wear away appreciably during a season.

To further the flexibility of the strips 1, the rods 2 are spaced apart in the direction of the length of the strips 1, so that there is left a substantial portion of each strip which is unsupported, and therefore flexible. This flexibility serves a further purpose in that a piece of gravel tending to lodge or wedge itself between any two adjacent strips will, by the flexing action of these strips, be squeezed and worked free, so that the riffle is selfcleaning and nonclogging.

Preferably the spacer elements 3 are formed of short lengths of rubber tubing, for example, comparatively stiff garden hose. Thus they are compressible and their ends can be pressed tightly against the adjacent strips 1, which in themselves, of course, are somewhat compressible, by tightening up the nuts 20, thereby completely closing any joint between the spacers and the strips to prevent the entrance and secretion of gold in such crevices. Gold, when passed over riffles, has the peculiar property of working into minute cracks and fissures, for example, into nail holes, and a considerable quantity of gold might otherwise work into the holes through which the rods extend, or into the interior of the spacer elements 3, if the latter were not tightly pressed against the faces of the strips.

To make the unit easy to handle I prefer to employ frame elements such as the angle irons 5 at each end of a unit. The unit thus formed may be made of a size which is convenient for packing, and which is light in weight as compared to any rifle with which I am familiar, except one made of wood, and wooden riffles have the very serious disadvantage that they wear out rapidly. Such a unit as this, composed of strips which have parallel smooth faces, provides no anchoring means which will resist pulling the unit from the sand, clay and the like, indicated at S in Figure 2, which lodges between the riffle units. At clean-up time the riffle must be lifted from this mass of material to enable the collected material to be washed down the sluice box to afford access to the gold, and it has been found in practice that such a riffle as this is not difficult to lift out, even though the collected material may be of a clay-like nature, which in some instances becomes practically a cement, greatly resisting efforts to remove the riffle.

As mentioned above, it is preferable that the tread surface of the strips be placed on the upstream side. These tread surfaces, though made of worn tires, will ordinarily have left on them

certain irregularities of the tread pattern (see Figure 3) and these irregularities serve further to break up and riffle the water flowing over the unit.

While the strips have been shown extending transversely of the sluice box, this is only one way in which my invention may be manufactured, and indeed the pattern may be any which suits the convenience of the manufacturer or the desire of the user. Furthermore, instead of straight upper edges, the upper edge of each strip may be scalloped, as shown at 11 in Figure 3, or otherwise made irregular, and these irregularities may be staggered in successive strips to further break up the water flow.

It will be noted that the rods 2 are protected against contact of gravel, sand and the like, and from the scouring action created by the riffling, by the rubber spacer elements overlying these rods, and such protective elements would be valuable in prolonging the life of the riffle units, even though other spacer means were provided, as for example metal sleeves.

It is preferable that the strips be placed on edge, upstanding from the bottom 4 of the sluice box, since the fabric plies 18 effectively resist wear and serve to stiffen the riffles, but the strips might be otherwise placed without departing from the spirit of my invention as defined in the claims. The strips 1, being flexible, will vibrate under the action of the water, sand, gravel and gold, and this vibration will tend to segregate the material and to effect additional riffling of the water in addition to the property previously mentioned of freeing rocks which might tend to lodge between the strips, and this vibration, therefore, which cannot be present in a riffle made of any non-yielding material, presents a further advantage in this riffle.

What I claim as my invention is:

1. A riffle unit for disposition in a sluice box, comprising a plurality of flexible strips of rubber material, each having a scalloped edge, and supporting said strips disposed on edge in spaced-apart, parallel, face to face relation, with their scalloped edges uppermost, and with the scallops on adjacent strips arranged in relatively staggered relationship.

2. A riffle unit for disposition within a sluice box, comprising a plurality of readily flexible strips disposed on edge in face to face relation, rods extending through apertures in the strips from end to end of the unit, and spaced apart lengthwise of the strips, spacing tubes having a bore considerably larger than the rods, surrounding the rods, and of such an outside diameter and interposed between adjacent strips in such relationship thereto as to engage the strips from substantially their lower edges to above their centers, to stiffen the major part of each strip while leaving the strips' upper edges free to flex by the flow of material over the strips, and means to press the spacing elements into contiguous gripping engagement with the strips.
